SPADE FORK OR SIMILAR ARTICLE

Elizabeth M. Scott, Los Angeles, Calif.

Application December 7, 1946, Serial No. 135,345

Term of patent 14 years

(Cl. D39—1)

To all whom it may concern:

Be it known that I, Elizabeth M. Scott, a citizen of the United States, residing at Los Angeles, in the county of Los Angeles, State of California, have invented a new, original, and ornamental Design for a Spade Fork or Similar Article, of which the following is a specification, reference being had to the accompanying drawings, forming a part thereof, in which:

Fig. 1 is a perspective view of the front side of the spade fork or similar article, showing my new design;

Fig. 2 is a transverse sectional view thereof, taken through 2—2 of Fig. 1;

Fig. 3 is a vertical sectional view thereof, taken through 3—3 of Fig. 1.

I claim:

The ornamental design for a spade fork or similar article, substantially as shown.

ELIZABETH M. SCOTT.
